UNITED STATES PATENT OFFICE

HAROLD S. LION, OF CINCINNATI, OHIO, ASSIGNOR TO UNITED MILK CRATE CORPORATION, OF CINCINNATI, OHIO, A CORPORATION OF OHIO

METHOD OF AND CRATE FOR PACKING CONICAL ARTICLES

Application filed April 5, 1929. Serial No. 352,674.

This invention relates to a method of packing conical articles and to a crate more especially adapted to the purpose of transporting conical articles, as, for example, conical paper containers of a type now utilized to distribute milk.

An object of the invention is to provide a method of packing conical articles in such manner as to utilize approximately all of an available storage space for the placing therein of a maximum number of conical articles.

A further object of the invention is to provide a crate for containers or other articles designed with the purpose in view of utilizing the maximum of the available space of the crate for the storage of conical containers or articles.

A further object is to produce a crate having slanting supporting portions for the bases of conical containers or other articles arranged to situate a side wall or limiting surface of each of several containers or articles whose base rests upon a supporting portion in approximately parallel relation to desirably vertical side walls of the crate, to thus provide a packing space between each of upright conical containers or articles when placed in said crate and an adjacent upright conical container or article or a side wall of said crate adapted to preferably snugly receive an inverted conical container or article, whereby to make available approximately all of the storage space of the crate for the packing therein of a maximum number of conical containers or articles.

A further object is to provide a crate for duplicate conical articles having slanting supporting portions positioned in separate contiguous rows each of which is adapted to provide a common support for a plurality of conical articles and has width about equal to the diameter of the base of each of said duplicate conical articles, and is disposed to situate a limiting surface of the side wall of each article whose base rests upon a supporting

portion in approximately parallel relation to upstanding side walls of said crate, to thus provide a packing space between each of duplicate upright conical articles of each of said rows and an upright conical article of an adjacent row or an upstanding side wall of said crate adapted to receive an inverted duplicate conical article, whereby to make available approximately all of the storage space of the crate for the packing therein of a maximum number of conical articles.

A still further object is to provide a crate of the character mentioned, wherein means is provided for limiting movement of each of the upright and inverted conical articles longitudinally of the different slanting supporting portions.

Other objects and advantages of the invention will become apparent from the full description thereof now to be made, it being understood that the disclosure herein is merely illustrative and intended in no way in a limiting sense, changes in the method and in details of construction and arrangement of parts of the crate being permissible so long as within the scope of the claims which follow.

In the accompanying drawings forming a part of this specification,

Fig. 1 is a top plan view of a crate having the features of the invention, disclosing several upright and inverted conical containers or other articles packed in the crate in accordance with my new method;

Fig. 2 is a vertical sectional view thereof, taken substantially on line 2-2 in Fig. 1, disclosing, in full and in dotted lines, conical containers or articles packed in the crate;

Fig. 3 is a top plan view of a modified form of crate made in accordance with the invention, also disclosing conical containers or other articles packed in the crate in manner according to the invention;

Fig. 4 is a vertical sectional view of the

crate of Fig. 3, taken substantially on line 4—4 in said Fig. 3;

Fig. 5 is a fragmentary sectional view of a further modified form of crate; and

Fig. 6 is a fragmentary sectional view of a still further modified form of crate.

Referring to Figs. 1 and 2 of the drawings, I have there disclosed a crate 10 consisting of upright side walls 11, 12, 13 and 14 suitably secured together to provide a rectilinear structure, and a bottom 15 which may be secured to the lower portions of said side walls in any convenient manner.

As shown, the bottom 15 of the crate 10 consists of tie rods 16 suitably secured to the walls 11 and 12 and passing through openings 17 in spaced apart cross bars 18 extending between and secured to the walls 13 and 14 as indicated at 19. Spacing sleeves 20 upon the tie rods 16 and between adjacent cross bars, or between a side wall of the crate and a cross bar, retain the cross bars in their intended relation.

Desirably, the upper portion of each cross bar 18 may include a projecting ledge 21 arranged upon a slant to the horizontal, the width of each cross bar preferably being vertically disposed.

Each ledge 21, together with a part 22 of the tie rods 16 in proximity to the next adjacent cross bar 18 and at elevation lower than the ledge, constitutes a slanting supporting portion, designated 23, for the bases of a row of conical containers or articles A, and the slanting supporting portions 23 are arranged to situate a side wall or limiting surface of each container or article whose base rests upon a slanting supporting portion in parallel relation to the upright walls 11 and 12 of the crate, so that a packing space adapted to snugly receive an inverted container or article will be provided between each of the upright containers or articles of each of said rows and an upright container or article of an adjacent row or a side wall of the crate, the different rows of conical containers or articles being adapted to fill approximately all of the spaces of each of the said slanting supporting portions 23 for the dimension of the box between the walls 11 and 12 thereof, as very clearly disclosed in Fig. 2, and each row of conical containers or articles being adapted to fill approximately all of the spaces of each slanting supporting portion 23 for the dimension of the box between its walls 13 and 14.

As shown, when the upright conical containers or articles are in the crate, a portion of a side wall or limiting surface of each container or article lies contiguous with, or in close proximity to, an adjacent cross bar 18, or a side wall of the crate, so that movement of each upright conical container or article transversely of the slanting supporting portion 23 upon which it rests is thus precluded.

As will be seen, the bases of each of the several different rows of conical containers or articles between the walls 13 and 14 of the crate rest upon a common slanting supporting portion 23. Means for limiting movement of both the upright and the inverted conical containers or articles in direction lengthwise of the said common slanting supporting portions 23 may desirably consist of rods 24 extending between the walls 11 and 12 and arranged to separate the different conical containers or articles of each of said several rows, the said rods 24 as shown being situated in spaced relation to the bottom of the crate and being attached to the walls 11 and 12 as indicated at 25.

When the crate is applied to use, all of the upright conical containers or articles will preferably be placed in the crate before the invented conical containers or articles are inserted, and all of the said inverted conical containers or articles will preferably be first removed from the crate.

While I have described the containers or other articles to be packed in the crate as of conical configuration, this need not necessarily be so. As shown, the containers or articles are of general conical shape, but have their upper portions flattened out somewhat to receive a metal closure or sealing strip. Obviously, the bases of the containers or articles could be of configuration other than circular. For example, the basis could be more or less elliptical in shape.

Referring to the modified form of crate disclosed in Figs. 3 and 4, the upright walls may be of about the construction as already described, but the bottom 15' as here shown is of wood or other suitable material and includes slanting supporting portions 23' which are equivalents of the portions 23 of the form of the invention of Figs. 1 and 2. The bottom 15' may be supported upon the side walls in any convenient manner, as denoted at 26. The slanting supporting portions 23' extend the full distance between the walls 13 and 14, and rods 24' are for the purpose as already described. A portion of each upright conical container or other article adjacent the base thereof engages a vertical portion 18', or a side wall of the crate, in the same manner and to the accomplishment of the same advantage as before.

Referring to Fig. 5, the slanting supporting portions 23^a consist of tie rods 16^a above which are situated cross bars 18^a in the form of wires, which perform the same service as do the cross bars 18.

Referring to Fig. 6, the slanting supporting portions 23^b consist of a bottom 15^b supporting blocks 18^b, the bottom and blocks serving the same purpose as do the portions 23' of Figs. 3 and 4.

I claim as my invention:

1. A crate consisting of upstanding side

walls and a bottom having slanting supporting portions adapted to receive the bases of conical articles arranged in said crate in upright contiguous relation to each other, 5 the said slanting supporting portions being positioned in separate contiguous rows along said bottom and being disposed to situate a limiting surface of the side wall of each article whose base rests upon a supporting portion in approximately parallel relation to up- 10 standing side walls of said crate, to thus provide a packing space between each upright conical article in each of said rows and an upright conical article of an adjacent row 15 or an upstanding side wall of said crate adapted to receive an inverted conical article, whereby to make available approximately all of the storage space of the crate for the packing therein of a maximum number 20 of conical articles.

2. A crate consisting of upstanding side walls and a bottom having slanting supporting portions adapted to receive the bases of duplicate conical articles arranged in said 25 crate in upright contiguous relation to each other, the said slanting supporting portions being positioned in separate contiguous rows along said bottom each adapted to provide a common support for a plurality of conical 30 articles and having width about equal to the diameter of the base of each of said duplicate conical articles and being disposed to situate a limiting surface of the side wall of each article whose base rests upon a supporting 35 portion in approximately parallel relation to upstanding side walls of said crate, to thus provide a packing space between each duplicate upright conical article in each of said rows and an upright conical article of 40 an adjacent row or an upstanding side wall of said crate adapted to receive an inverted duplicate conical article, whereby to make available approximately all of the storage space of the crate for the packing therein of 45 a maximum number of conical articles.

3. A crate consisting of upstanding side walls and a bottom having slanting supporting portions adapted to receive the bases of duplicate conical articles arranged in said 50 crate in upright contiguous relation to each other, the said slanting supporting portions being positioned in separate contiguous rows along said bottom each adapted to provide a common support for a plurality of conical 55 articles and having width about equal to the diameter of the base of each of said duplicate conical articles and being disposed to situate a limiting surface of the side wall of each article whose base rests upon a support- 60 ing portion in approximately parallel relation to upstanding side walls of said crate, to thus provide a packing space between each duplicate upright conical article in each of said rows and an upright conical article of 65 an adjacent row or an upstanding side wall

of said crate adapted to receive an inverted duplicate conical article, whereby to make available approximately all of the storage space of the crate for the packing therein of a maximum number of conical articles, and 70 means for limiting movement of each of the upright and inverted conical articles longitudinally of the different slanting supporting portions.

In witness whereof, I have hereunto set 75 my hand this 1st day of April, 1929.

HAROLD S. LION.
